UNITED STATES PATENT OFFICE.

ARTHUR G. HATCH, OF DULUTH, MINNESOTA.

APPARATUS FOR MAKING CONCRETE BRICKS.

1,425,590.

Specification of Letters Patent. Patented Aug. 15, 1922.

Application filed July 7, 1921. Serial No. 482,990.

To all whom it may concern:

Be it known that I, ARTHUR G. HATCH, a citizen of the United States, residing at Duluth, in the county of St. Louis and State 5 of Minnesota, have invented certain new and useful Improvements in Apparatus for Making Concrete Bricks, of which the following is a specification.

This invention relates to a new and improved means and method for making brick, and more particularly for making brick from concrete or similar material.

Concrete or material of like nature must be handled differently from plastic material 15 such as clay, in the making of bricks. It is impractical to make concrete bricks by any continuous process machine of a type such as those used in extruding clay in brick making. The concrete must be supported 20 until at least the initial set has taken place and this necessity for support involves the provision of large numbers of molds where concrete brick construction is undertaken on a large scale. This is due to the fact that 25 the molds must be occupied by each brick for a considerable period of time. This requirement for a large number of molds involves very considerable expenditure for a plant and also requires a large space for operation, and relatively high labor costs in 30 concrete brick making as now generally practiced.

It is an object of the present invention to provide a new and improved means and apparatus for forming concrete brick.

It is a further object to provide molds which are compact in form and so adapted for placing that pouring of the concrete may be accomplished with a minimum 40 amount of labor.

It is an additional object to provide molds which are subdivided into easily handled sections and which are formed in such manner that the brick may be readily removed 45 from the mold without danger of injury to the brick.

Other and further objects will appear as the description proceeds.

Broadly, my invention comprises the formation of a wooden decking or similar plane surface and the attachment to that surface of vertical septums, the septums being adapted to receive rows of bricks between successive pairs. There are further provided pallets fitting between the spaced septums, the pallets being provided with

transverse septums properly spaced to form bricks of the required size. These pallets are freely removable from between the fixed septums attached to the decking and are 60 made of such length as to be readily handled.

I have illustrated a preferred embodiment of my invention in the accompanying drawing, in which—

Figure 1 is a plan view showing my brick-forming mold construction in assembled relation;

Figure 2 is a longitudinal section of Figure 1;

Figure 3 is a transverse section on line 3—3 of Figure 1;

Figure 4 is a side view of a pallet with bricks therein;

Figure 5 is a top view of Figure 4; and

Figure 6 is a view of a tool used in handling pallets.

Referring to the drawing, the decking 7 is provided with a vertically extending side member 8. Running parallel to this side member are the equally spaced longitudinal septums 9. As best shown in Figure 3, these septums 9 are preferably formed of flat pieces of metal and have a portion 9' in engagement with the decking and extending the full width between adjacent septums. Fitting between adjacent pairs of septums are the pallets 10 best shown in Figures 4 and 5. These pallets consist of flat wooden strips 11 slightly less in width than the distance between adjacent septums 9. The pallets are made of convenient length, those shown being six bricks long. At either end the pallets are provided with metal handling clips 12, these clips extending under the pallet at 13 and having sloping portions 14 at the ends of the pallet which facilitate tilting the pallets in removing them. The upper ends of the clips 12 are curved at 15 and are provided with slots 16. The slots 16 are adapted to receive the bar 17 on the tool 18 shown in Figure 6. The upper face of the wooden pallet member 11 carries the sheet metal facing 19 which is formed with upwardly extending reversely bent portions 20, these portions 20 defining the limits of the bricks.

In the use of my apparatus, the pallets are placed between the septums until the desired area of the mold deck is covered. 110 The brick-forming mix is then poured upon the deck and is evenly distributed by means

of a lute or similar tool. The material is then struck off smoothly, even with the upper surface of the septums 9 and the transverse portions 20. When the initial set has 5 taken place, the pallets are removed by inserting tools 18 at either end and may then be carried by hand or trucked to the desired location, where by inverting the pallet the green bricks easily drop from the pallet and 10 may be stored and cured until ready for use. An important feature of my invention lies in the ease with which a special colored face may be formed upon the bricks. After the material has been struck off in the forms 15 or molds, the entire surface may be easily washed with colored grout or with a thin facia mix. If desired the septums and transverse portions of the pallets may be made slightly lower than the desired brick 20 size, and after the body material has been struck off and leveled by means of the septums, an additional thin layer of a facia mix may be smoothed on with a strikeboard or trowel. 25 My apparatus is adapted to mold bricks in a small area with a minimum of labor cost. The material, as stated, may be dumped in large masses and smoothed out to form a large number of bricks at a single 30 striking-off operation. The pallets are easily handled and the bricks readily drop from the pallets when they are removed from the septums and inverted. This dis-

charge of the bricks is aided by the slight flexibility or resilience of the pallets, which 35 may be slightly bent or flexed in discharging the bricks.

I claim:

1. Apparatus for making concrete brick or the like, comprising a molding deck, 40 spaced parallel septums extending vertically from the deck, removable pallets fitted between the septums, said pallets carrying members adapted to form the lower and end faces of the bricks, and being provided with 45 means whereby they may be vertically removed from between the septums, the body portions of the pallets being adapted to be flexed to facilitate removal of the bricks from the pallets. 50

2. Apparatus for making concrete brick or the like, comprising a molding deck, spaced parallel septums extending vertically from the deck, said septums being formed of metal, removable pallets fitted 55 between the septums, the bodies of the pallets being formed of wood and being faced with metal having upwardly extending portions adapted to form the end faces of brick, said 60 pallets being provided with handling clips whereby they may be removed from the molding deck. 65

Signed at Duluth, Minnesota, this 30th day of June, 1921.

ARTHUR G. HATCH.
